(57) CLAIM

The ornamental design for a “non-slip hair band,” as shown and described.

DESCRIPTION

FIG. 1 is a perspective view of a non-slip hair band showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a state of use;

FIG. 9 is a perspective view thereof, showing a state in use; and,

FIG. 10 is a perspective view thereof, showing another state in which the non-slip hair band is used as a headwrap. The broken lines shown in the figures depict portions of the non-slip hair band that form no part of the claim.
